Paul B. Spranger, Fullerton, Calif., assignor to Columbia
Broadcasting System, Inc., New York, N.Y., a corpo-
ration of New York

Filed Mar. 25, 1966, Ser. No. 1,636

Term of patent 14 years

(Cl. D26—14)

FIGURE 1 is a perspective view of an amplifier or similar electronic apparatus embodying my new design;

FIGURE 2 is a front elevation thereof;

FIGURE 3 is an end elevation thereof, as viewed from the right in FIGURE 2;

FIGURE 4 is a rear elevation thereof;

FIGURE 5 is an end elevation thereof, as viewed from the right in FIGURE 4;

FIGURE 6 is a top plan view thereof;

FIGURE 7 is a bottom view thereof;

FIGURE 8 is a sectional view thereof taken on line 8-8 of FIGURE 2, showing surface contour only;

FIGURE 9 is a perspective view corresponding to FIGURE 1 but showing a second embodiment of my new design; and

FIGURE 10 is a perspective view corresponding to FIGURES 1 and 9 but showing a third embodiment of my new design.

The embodiments of FIGURES 9 and 10 correspond generally to the embodiment of FIGURES 1-8, so that the various views 2-8, inclusive, are generally applicable to each of the embodiments of FIGURES 9 and 10.

The dominant features of the design reside in the portions shown in solid lines.

I claim:

The ornamental design for an amplifier or similar electronic apparatus, substantially as shown and described.
